VIBRATORY CONVEYER

James A. Flint, Columbus, Ohio, assignor to The
Traylor Vibrator Company, a corporation of
Colorado

Application June 18, 1935, Serial No. 27,230

4 Claims.

(Cl. 34—38)

This invention relates to a combined cooler and conveyer, particularly of the vibratory type.

An object of the invention is to provide a device which will simultaneously cool and convey material, such as table salt, glauber salt, synthetic plastics or any granular material, whereby it may be cooled as rapidly as possible after being subjected to a heat treatment for drying said material.

10 Another object of the invention is to provide a very efficient cooling device which will form material of the type above mentioned into thin layers, the particles of which are constantly moving and rolling over, thereby providing a maximum surface exposure and presenting new surfaces thereof to a cooled trough in which they are contained and conveyed.

Still another object of the invention is to provide a combined cooler and conveyer whereby hot 20 particles of material may be received at one location and transferred to another location, and during said transfer they will be sufficiently cooled to be capable of ready handling, the time and distance of travel, and thus the cooling time, 25 being reduced to a minimum.

Other objects of the invention will appear hereinafter, the novel features and combinations being set forth in the appended claims.

Fig. 1 is a side elevational view of the combined conveyer and cooler of my invention showing the discharge end thereof;

Fig. 2 is a side elevational view of the material receiving end of the device of Fig. 1 and, when placed end to end with Fig. 1, discloses 35 the complete device;

Fig. 3 is a transverse sectional view taken on the line 3—3 of Fig. 2 looking in the direction of the arrows;

Fig. 4 is a longitudinal sectional view of the 40 vibratory motor of my invention taken on the line 4—4 of Fig. 2 looking in the direction of the arrows;

Fig. 5 is an enlarged detailed sectional view 45 showing the mode of attaching the cover plate to the conveyer trough or deck;

Fig. 6 is an enlarged elevational view of the device of my invention showing particularly the driving motor therefor, with part of the conveyer deck shown in section to illustrate the cooling means;

Fig. 7 is an enlarged detailed sectional view 50 showing the supporting means for the fluid pipe and the flexible attachment between said conveyer deck and said fluid pipe;

55 Fig. 8 is a transverse sectional view similar to

the view of Fig. 3 showing a modified form of conveyer trough;

Fig. 9 is a plan view of the discharge end of another modified form of a combined cooler and conveyer deck;

Fig. 10 is a side elevational view of the device of Fig. 9;

Fig. 11 is a front elevational view of the device of Figs. 9 and 10;

Fig. 12 is a transverse sectional view on the line 12—12 of Fig. 10 looking in the direction of the arrows; and

Fig. 13 is a transverse sectional view on the line 13—13 of Fig. 10 looking in the direction of the arrows.

In a process of manufacturing numerous materials, particularly of a granular structure—examples of which are table salt, glauber salt and synthetic plastics—it is often necessary to heat the material to a relatively high temperature to 20 remove moisture therefrom. After this heating or drying process is completed, it is often necessary to heat the material to a relatively high temperature to remove moisture therefrom. After this heating or drying process is completed, 25 it is necessary to cool the material before it may be easily handled or used and my invention relates to a device particularly adapted to cooling such material and for transporting it from a position where it has been subjected to the mentioned heat treatment to a position where it may be handled after being cooled.

To this end I provide the combined cooler and conveyer illustrated in the drawings comprising a vibratory deck A. Said deck A is subjected to 35 vibratory motion by vibratory motors B which are effective to impart a conveying action to any material carried on said deck A. In the operation of said combined cooler and conveyer, hot material is fed to the deck through a chute 20 and 40 falls into a trough 21 of said vibratory deck A. The material is then conveyed along said trough 21 where it is subjected to a cooling action, and discharged at the outlet chute 22, in a relatively cool condition, into any desired receptacle or conveyer.

The vibratory deck A comprises the trough 21 which is substantially U-shaped in cross section, as best seen in Fig. 3. Said trough is formed by side walls 23 connected by an arcuate bottom 50 wall 24. Reinforcing side ribs 25 may be provided at spaced intervals along each side of the trough 21 to increase the rigidity thereof. Spaced appreciably above the bottom wall 24 of the trough 21 is a material supporting bottom 26. 55

It will be evident that the material received by the chute 20 will rest on the material supporting bottom 26 and be conveyed along said bottom 26 and discharged at the outlet chute 22. Within the trough 21 and extending longitudinally thereof is a pipe or conduit 27 attached to a source of, and adapted to carry a cooling fluid, such as water. This pipe 27 is provided with spaced spray nozzles 28 which are adapted to spray the cooling fluid over the lower surface of material supporting bottom 26 and adjacent the side walls 23 immediately below said material supporting bottom 26. Said nozzles are preferably so spaced as to assure the spraying of the entire area of the bottom of the material supporting bottom 26 as illustrated in Fig. 6. To this end, the spray from adjacent nozzles 28 may slightly overlap on the area covered on said material supporting bottom 26. After the cooling fluid has sprayed on the lower side of said material supporting bottom 26, it will accumulate in the bottom of the trough 21 and be carried away by the outlet 29.

The pipe 27 is supported adjacent its ends by uprights or standards 30 and 31, which carry adjustable brackets 32 and 33 adjacent their tops, which brackets are rigidly attached to the ends of said pipe 27, as by welding. An adjustment of the height of each end of said pipe 27 is provided by co-operating threaded rods 34 and 35 and the nuts 36 and 37. It will thus be seen that the pipe 27 is stationary and does not vibrate with the trough 21.

To provide for the resultant relative movement between said pipe 27 and the deck A, flexible connections are provided between the trough 21 and the ends of said pipe 27. There, of course, will be similar flexible connections at each end of said pipe 27 and trough 21 and somewhat similar connections 22', 43' from deck A to outlets 22 and 29. In Fig. 7, the structure of these connections is illustrated in detail. Said structure comprises a flared sleeve 38 having an outer peripheral flange 39 adapted to be connected to the trough 21 to form a water-tight connection therewith by means of a gasket 40 and appropriate nuts and bolts 41. The sleeve 38 has a restricted end 42 which provides a circumferential groove over which is adapted to be slipped one end of a flexible sleeve 43, which may be made of rubber. A retaining ring 44 is provided for attaching the flexible sleeve 43 to the end 42 of the flared sleeve 38. The other end of the flexible sleeve 43 is attached to the pipe 27 by a retaining ring 45. It is thus seen that a fluid-tight connection is provided between the pipe 27 and the trough 21 at each end thereof which allows complete freedom of movement of said trough 21 with respect to said pipe 27. Therefore, the vibrations of the trough 21 will not be transmitted to the pipe 27.

It is preferred that the trough 21 be completely covered and to this end I provide a plurality of spaced standards 46 on each side of said trough 21 which carry a plurality of longitudinally extending plates 47 positioned above the trough 21. These plates 47 are provided with downwardly extending threaded rods 48 adapted to be screw-threadedly attached to the standards 46. Clamping nuts 49 are also provided to make a rigid connection between the standards 46 and the rods 48. Adjacent the inside edge of each of the plates 47, there is provided a longitudinally extending angle member 50 which is rigidly attached to said plates 47, as by welding.

Between the angle members 50 and the top edges 51' of the trough 21, there extends a flexible web connection 51 made of flexible material, such as canvas or rubber. This web connection not only extends along the longitudinal sides of the trough 21 but also extends across the ends thereof. Clamping plates 52 are provided to clamp the top edges of the web connection 51 to the angle members 50 and the clamping plates 53 are provided for connecting the lower edges of the web connection 51 to the top edges 51' of the trough 21. Appropriate nuts and bolts may be provided for clamping the clamping plates 52 and 53 to the angle members 50 and the trough 21, respectively.

A cover plate 54 is provided which is pivoted to one of the angle members 50 upon hinges 55, best seen in Fig. 5. Lifting handles 56 are provided for the cover 54 near the edge thereof removed from the hinges 55. It is thus obvious that the cover plate 54 may be pivoted about the hinges 55 to provide access to the trough 21 but, under normal conditions, said trough will be completely closed. This prevents contamination of the material being cooled.

As illustrated in Figs. 1 and 2 of the drawings, a plurality of vibratory motors B, of which there are two illustrated, are employed for imparting a vibratory movement to the deck A. The number of vibratory motors which will be employed will be determined by the length of the vibratory deck A and by the size thereof and thus may vary within wide limits. The vibratory motor B comprises a base casting 57 which is of heavy construction, being made of cast iron, which casting is provided with a longitudinally extending opening 58 through which extends a plurality of spaced spring leaves or vibrator bars 59, best illustrated in Fig. 4. These spring leaves 59 are clamped adjacent their ends between bosses 60 on the base casting 57 and clamping plates 61, by means of clamping screws 62. Appropriate spacers 63 are provided between each of the spring leaves 59 adjacent their clamped area. It is thus evident that each of the spring leaves 59 is mounted for free flexure.

Rigidly clamped to the center of the spring leaves 59 is an armature shaft 64 having an opening 65 therein through which said spring leaves 59 extend. The armature shaft 64 has a boss 66 extending into the opening 65 to bear against one of the end spring leaves 59. The armature 64 on that side of the leaf spring 59, 63 opposite the boss 66 comprises a web 68 which carries a plurality of clamping screws 67 which extend through the web 68 in position to bear against a clamping plate 69 which fits against another end leaf spring 59. Appropriate spacers 70 are stacked alternately between the spring leaves 59 in alignment with the boss 66 and the clamping plate 69. It is thus evident that upon the screwing home of the clamping screws 67, the armature shaft 64 will be rigidly attached to the centers of the spring leaves 59 and consequently the leaf spring 59, 63, 70 resiliently connects the armature 64 to the base casting 57.

The base casting 57 is provided with a transversely extending opening 71 through which the armature shaft 64 extends. Said armature shaft 64 carries a bracket 72 upon which is mounted an armature 73 formed of laminated sheet steel, and rigidly attached to said brackets 72 by tie bolts 74.

The armature shaft 64 also carries a pair of integral brackets 75 which are rigidly clamped 75

to the trough 21 by means of clamp bolts 76 which co-operate with appropriate brackets 77 rigid with said trough 21. The axis of the armature shaft preferably passes through the center of 5 percussion of the deck A or, if a plurality of motors B are employed, through the center of percussion of a selected portion of said deck A. In addition, a bracket 78 (Figs. 1 and 2) may be provided which is rigidly clamped to the trough 10 21 at one end by appropriate clamp bolts 79 and brackets 80 and at the other end to the armature shaft 64 adjacent the bracket 72. If desired, this bracket 78 may be omitted but I prefer to employ it so that the vibratory movement 15 of the armature shaft 64 will be more widely distributed along the trough 21. This bracket 78 will also make a more rigid deck construction and will reduce any tendency of buckling by said trough 21. In addition, this additional bracket 20 78 reduces the static twisting moment armature shaft 64 would otherwise place on the leaf spring 59, 63 due to the static load presented by the weight of the deck A. That is, the static moment transferred to armature shaft 64 through 25 bracket 78 about the leaf spring 59, 63 as a fulcrum will oppose the static moment transferred thereto through brackets 75, thus reducing the twisting of the leaf spring 59, 63. It may be noted that the bracket 78 may be omitted as 30 illustrated in Fig. 6, but it is preferred to include the bracket 78 to compel the trough 21 more effectively to partake of the vibrations of the armature 64 without distortion, and for the other reasons above mentioned.

35 The base casting 57 is preferably flexibly supported upon standards 81, of which there is one adjacent each side, which standards 81 are mounted on coil springs 82 adapted to fit cupped recesses 83 in said standards 81 and to be carried adjacent their bottom end in clamp plates 84 which may be rigidly bolted to foundation 85. Due to the weight of the base casting 57, only small vibrations will be manifest therein but it is preferred that these vibrations be not transferred to the foundation 85 and thus the coil springs 82 are provided to make a flexible support for said base casting 57.

50 Rigidly attached to the base casting 57 is a pair of spaced U-brackets 86. Mounted upon the U-brackets 86 is a field structure for the vibratory motor B which comprises a U-shaped magnetic field core 87 preferably formed of sheet steel laminations which are carried between brackets 88 and are rigidly attached thereto by 55 tie bolts 89. Surrounding each leg of the magnetic field core 87 is a field coil or solenoid 90 which is held in place by plate 91, which plate 91 is mounted on the brackets 88 by tie bolts and spacers 92. The entire field assembly, comprising the U-shaped magnetic field 87, constitutes an electro-magnetic motor having spaced poles separated by air gaps from the adjacent armature 73.

55 The field coils 90 and the brackets 88, as well as the other parts rigidly attached thereto, are adjustably supported on the U-shaped brackets 86 by a plurality of threaded rods 93. These threaded rods 93 may be adjusted with respect to the U-shaped brackets 86 to adjust the air gaps 70 between the poles of U-shaped magnetic core 87 and the armature 73. These air gaps are so adjusted that the armature 73 and the field 87 will never come into contact with each other during operation. Clamping bolts and nuts 94 are provided for clamping the threaded rods 93 in any

adjusted position, as allowed by the split condition of brackets 86.

The field coils or solenoids 90 may be connected either in series or in parallel and when energized from any source of constant frequency alternating current as, for example, a source of commercial alternating current of 25, 30, 50 or 60 cycles, the armature 73 will be attracted to the field 87 twice during each cycle of operation and will be effectively released when the flux in the magnetic field 87 passes through zero in changing its direction. Therefore, the armature 73 will operate at a frequency of 7200 cycles per minute for a current of 60-cycle frequency. The operating frequency thereof for currents of 25, 30, 50 and 60 cycles per second will be obvious. When the armature 73 is attracted to the field 87, the spring leaves 59 will be deflected to store energy therein. When the flux in the magnetic field 87 passes through zero or approaches zero, as aforesaid, the armature 73 will be released and the energy stored up in the spring leaves 59 will be effective to move the armature 73 away from the magnetic field 87. It is thus evident that when the field coils 90 are energized from a source of alternating current, the armature shaft 64 will be vibrated at a frequency twice the frequency of the energizing current. In order to control the amplitude of vibration of the armature 73 and thus the rate of travel of the material along the bottom 26, a variable rheostat may be placed in series or in parallel with said field coils 90.

It is also contemplated that the field coils 90 be energized simultaneously from sources of alternating current and direct current, generally termed "mixed current" particularly if a frequency of 3000 or 3600 vibrations per minute is desired and the current available has a frequency of 50 or 60 cycles per second. In practice, I never use mixed currents for frequencies of 25 or 30 cycles per second as the resulting rate of vibration is below that desired for a thoroughly fluid bed. That is, a source of direct current, such as a direct current generator, is connected in series with the field coils 90 leading to a source of alternating current. As a consequence, there will be no actual reversal of current flow in the field coils 90 and the armature 73 will be attracted only once during each cycle 50 of the alternating current source. Under these conditions, the armature 73 will operate at a frequency of 3600 cycles per minute where the source of alternating current is 60 cycles per second. The operating frequency of armature 73 for 55 currents of 25, 30, 50 and 60 cycles per second will be equal to their frequency rather than twice the amount as was the condition when alternating current alone was employed. Such a system for operating a screen motor from "mixed current" 60 is disclosed in my patent for an Electric reciprocating motor, No. 1,846,326, granted February 23, 1932.

The operating frequency is preferably as high as possible and the angle of vibration of the deck, 65 as pre-determined by the inclination of armature shaft 64, is so related to the frequency of vibration that the downward component of movement of the material supporting bottom 26 is at such a rate that any material thereon will 70 fall at a lower rate and thus not ride as a dead load on said bottom 26. That is, the deck bottom 26 will move downwardly faster than a particle will fall, whereby particles will not ride down on the bottom 26. The bottom 26 will thus never 75

carry the material as a dead load but, when moving upwardly, will strike downwardly moving particles a sharp blow, similar to a baseball bat striking a ball, and thereby throw or impel the particles through space, through which they travel in a series of hops down the bottom 26 only contacting therewith at intervals and then only for a time sufficient to receive another blow or impulse. Where the operating frequency of the trough 21 is 7200 vibrations per minute, and the amplitude of vibration is $\frac{1}{4}$ in. the angle of inclination of the armature shaft 64 may be 10 degrees, though 15 degrees is a common setting. For lower frequencies, the angle must be increased to compensate therefor. It is contemplated that angles as high as 40 degrees may be employed where the lower vibrating frequencies, above mentioned, are employed. As a consequence, the natural period of vibration of the deck A, and parts rigid therewith, will be independent of the actual load thereon and will be constant at a definite value. Where lower frequencies are employed, the angle of inclination of shaft 64 will be increased to maintain this condition.

It is to be noted that the trough 21 is supported entirely from the armature shafts 64 and as they are rigidly attached to said trough 21 the vibratory movement of the armature shaft 64 will be transferred to said trough 21. Flexible connections are, of course, provided between the trough 21 and any structure which is attached thereto whereby the vibrations will be confined to said trough 21. Said trough 21 and the armature 73 and any parts which are rigidly attached to either therefore constitute a vibratory structure which is vibrated by the motor B. This vibratory structure will have a natural period of vibration which is determined primarily by the weight thereof and by the restoring force of the spring leaves 59. That is, the restoring force of the spring leaves 59 is so related to the weight of the vibratory structure that the natural period of vibration of said vibratory structure will be pre-determined at a desired value. In practice, it has been found to be extremely desirable to pre-determine this natural period of vibration of the vibratory structure at a frequency which is near to, but slightly different from, the frequency at which the armature 73 of the motor is vibrated. For example, if the armature 73 is vibrated by a current having a frequency of 60 cycles per second and at a frequency of 7200 cycles per minute, the natural period of the vibratory body is preferably selected at a value slightly above or slightly below 7200 cycles per minute, for example, at 7000 or 7400 cycles per minute.

It is entirely possible, but not desirable, to operate the device by pre-determining the natural period of vibration of the vibratory structure at exactly the period of vibration of the armature 73 which, in the example given, would be 7200 cycles per minute. It has been discovered, however, that if the period of vibration of said vibratory body is in exact resonance with the frequency of vibration of the armature 73, the amplitude of vibration of the deck A will vary appreciably with the load which is placed on said deck or, in other words, with the amount of material carried on the material supporting bottom 26.

In addition, it has been found that when no material whatever is carried on the material supporting bottom 26, there is danger of the armature 73 striking the poles of magnetic field core

81 and causing damage to either or both if exact resonance is maintained. This is due to the fact that when a vibratory body is operating at its natural frequency the energy necessary to vibrate said body is represented only by the frictional losses thereof and there is a possibility of the amplitude of vibration becoming unduly large. However, by vibrating the vibratory structure at a period slightly different from its natural period, either above or below the natural period, the vibrations thereof are forced and there is always a minimum amount of artificial load on said vibratory structure. This prevents any damage to the motor when the actual physical load—for example, the material carried on the bottom 26—is reduced to zero. In addition, it means that the variations in the actual physical load represented by the material carried on the bottom 26 will not have a great effect upon the amplitude of vibration of the deck A. As a consequence, the amplitude of vibration of said deck A will be substantially constant regardless of the actual physical load carried on the material supporting bottom 26.

Furthermore, by operating the vibratory structure at a frequency which is near its natural period, the amount of energy necessary to vibrate said vibratory structure is very materially reduced over what it would be if said vibratory structure was not operated near its natural frequency but were operated at a frequency distantly removed therefrom. This results in a great saving in operating costs, due to the use of a small amount of current, and makes possible the employment of a motor B which is of much smaller size than would otherwise be required. It will be evident, of course, that where a plurality of motors is employed to operate a single deck A, these motors will be operated in synchronism and in phase.

It is to be noted that the axis of vibration of the armature shaft 64 is parallel with the longitudinal axis of said shaft 64 and this axis forms an acute angle with the trough 21 and the material supporting bottom 26. This acute angle may vary between 10 and 40 degrees and in practice is usually set at 15 or 20 degrees. This angle is very important and it is so selected that at the rate of vibration of the deck and for a minimum operating amplitude of vibration the time of downward movement of the deck, between its extreme positions, during each oscillation, will be greater than the time the material will fall this distance. This means that the bed of materials will not operate as a dead load on the deck and will therefore not appreciably affect the natural period of vibration thereof, regardless of the actual load thereon. The natural period of operation of the deck is therefore independent of the load thereon. Due to the mode of vibration of the trough 21, the vibratory action of the bottom 26 will have both a vertical and a horizontal component. The vertical component will be effective to impel the particles of material upwardly from the bottom 26 and the horizontal component will be effective to transfer said particles in the direction indicated by the arrows 95. Due to this construction, the material will therefore be effectively conveyed from the material receiving end adjacent the chute 20 to the material discharge end adjacent the chute 22.

The action of the vibratory bottom 26 on the particles of material being cooled and conveyed is particularly effective to cool said particles in a minimum of time. There are a number of rea-

sons for this. In the first place, even though the material may be first received on the bottom 26 from the chute 20 in a pile, the vibratory action of said bottom 26 will be effective to form said material in a relatively even layer over the entire surface of the plate 26, as is illustrated in Fig. 3. This assures that the material will not travel down the bottom 26 in a pile, under which condition the inner particles would not be properly cooled. In addition, the entire mass of material effectively floats with respect to the bottom 26, as it makes contact therewith only at intervals of time for, as soon as a particle touches the bottom 26, it is immediately thrown into the air. Due to this particular action, each individual particle is spaced from each other individual particle and there is a complete absence of packing or compacting of the particles into a solid mass. The entire mass of materials is fluid-like and appears to flow somewhat like water. Not only are the individual particles slightly separated and thus exposed on their entire surface to the surrounding air but the constant impacting thereof when they strike the bottom causes them to rotate or revolve continuously, insuring complete freedom of movement thereof and resulting in the contacting of first one surface area thereof and then of another surface area thereof with the cooled bottom 26. Each particle is thus turned over very frequently or continuously to present all sides thereof downwardly toward the cooled upper surface of the deck bottom 26. This combined action is very effective to cool the entire mass of particles as it is transported along the bottom 26. This action will also induce rapid evaporation of excess moisture from granular materials, which evaporation would have a cooling effect on such material.

In Fig. 8 of the drawings, I have shown a slight modification of the material supporting bottom. In this form, a material supporting bottom 96 is provided which is trough-shaped and has tapering side walls 97. It is evident that in this construction the side walls 97, as well as the bottom 96, are cooled by the direct action of the cooling fluid which issues from the nozzles 28. The construction of this form of my invention is otherwise of the type illustrated in Figs. 1 to 7, inclusive. This form is particularly useful if the material to be cooled is of unusually high temperature when received from the chute 20 and removes any tendency of warping of the side plates 23 when such extremely high temperature material is to be cooled.

Figs. 9, 10, 11, 12 and 13 illustrate another form of my invention. In this form of my invention there is provided a deck C having side walls 98 and a bottom wall 99. Said deck C carries a trough 100 having a material supporting bottom 101 with tapering side walls 102. Extending longitudinally from the lower surface of the bottom 101 of said trough 100, there is provided a downwardly extending flange 103. This flange preferably extends substantially the entire length of the trough 100. Projecting laterally of the deck C and between the side walls 98 thereof is a plurality of flanges 104 which are attached at their tops to the trough bottom 101 and the side walls 102. The flanges 103 and 104 are effective to divide the lower surface of the bottom 101 into a plurality of separate areas.

Each of these separate areas is provided with an individual cooling means comprising an individual pipe 105 which extends into the deck C and is provided with a plurality of spray nozzles

106, of which there are two for each pipe 105, as illustrated in the drawings. It is evident that the number of nozzles may be increased or reduced as desired. The pipes 105 are supported by brackets 107 on longitudinally extending angle members 108 and are connected by downwardly extending flexible hose 109 to a common pipe 110 which carries the cooling medium, such as water. If desired, individual valves may be provided for the pipes 105 whereby individual control of the 10 sections of the trough bottom 101 is possible.

As illustrated in the drawings, a vibratory motor D, or preferably a plurality of said motors, may be provided for vibrating the deck C. It is to be understood that the motor D is essentially 15 of the same structure as the motor B which was above described in detail. It will also be understood that the structural details of the features of the form of my invention illustrated in Figs. 9 to 13, inclusive, are essentially the same as those 20 of the device of Figs. 1 to 7, inclusive, unless a modified structure is indicated. It will also be evident that the above described mode of operation of the device of Figs. 1 to 7, inclusive, will also apply to the Figs. 9 to 13, inclusive. 25

As illustrated in the drawings, the angle members 108 are supported from the base casting 111 of the motor D by supporting plates 112 and by angle members 113. If desired, said angle members 108 may be supported from a foundation by 30 standards similar to the standards 46 of Figs. 1, 2 and 3. This latter method of supporting the angle members 108, with the resulting support for the pipes 105, may be preferred, for the base casting 111 is subjected to slight vibrations. 35

The deck C is rigidly attached to the armature shaft 114 of the motor D by downwardly extending plates 115 which co-operate with a T-head 116 formed integral with the armature shaft 114. Appropriate cap screws 117 are provided for rigidly attaching the T-head 116 and the plates 115. The armature shaft 114 is also provided with an upwardly extending boss 118 which carries the bracket plates 119 which also attach the armature shaft 114 to the deck C. As the deck C is supported by the motor D through the armature 114 and through the plates 115 and 119, it will be evident that by placing plates 119 to the rear of the leaf spring 120 of the motor D, the twisting torque on said leaf spring 120, which would be 5 present were plates 119 omitted, is appreciably minimized.

It will, of course, be evident that the deck C must vibrate with respect to the pipes 105 and to allow for this relative movement flexible water-tight connecting means 121, best seen in Fig. 12, are provided between the side walls 98 of said deck C and said pipe 105. Clamping means of the type illustrated in detail in Fig. 7 may be here employed if desired.

It may also be mentioned that the base casting 111 of the form of my invention illustrated in Figs. 9 to 13, inclusive, is slightly different from that of the base casting 57 of the form of Figs. 1 to 7, inclusive, in that said casting has a transversely extending groove 122, which may be seen by referring to Fig. 13. This provides for the removal of the armature shaft 114 by lifting it vertically upwardly from the base casting 111 after leaf spring 120 is removed and provides room for 7 the upwardly projecting boss 118.

To review briefly the mode of operation of my invention as represented by any of the forms thereof, the material is fed to one end of the trough 21 or 100 through a chute, such as chute 7

20 of Fig. 2. This trough is vibrated at a very high frequency and in the case where a 60-cycle current is employed the frequency may be 7200 cycles per minute. A high frequency of vibration is very important because of the action on the material in making it fluid-like and constantly impacting the particles thereof to turn them over and expose all surfaces to the air and to the cooled trough bottom. In addition, the device can be operated directly from a commercial source of alternating current without requiring the inter-position of any frequency changing device, such as a motor generator set. This is of extreme practical value in reducing the initial cost. It also eliminates all rotary machinery, thus maintaining upkeep and break-downs at a minimum.

The particles in flowing down the trough 21 or 100 will contact with the bottom 26 or 101 which is cooled by the cooling medium which issues from the nozzles 28 or 106. Each particle of material will thereby be effectively cooled by the time it reaches the discharge end of the trough 21 or 100. The trough A or C will be vibrated at a frequency which is near to, but not exactly equal, its natural period of vibration, whereby the amplitude of vibration thereof will be substantially constant irrespective of any variations in the physical load carried thereby and will require a relatively small amount of energy to effect a vibrating action and thus will require relatively small vibratory motors B or D. The rate of travel of the material may be controlled by a field rheostat, because by means of the latter the amplitude of vibration may be regulated. By adjusting the rate of travel of the material, due consideration may be given to the time it must be treated to be completely cooled. Thus material received very hot may travel slowly over the bottom 26 while material received moderately warm may travel faster.

It is thus seen that a cooling device which also operates as a conveyor is produced which is very efficient in that it cools material in a minimum time interval and also conveys said material from a point where it has been dried or otherwise treated with heat to a point where it may be placed in receptacles or conveyors for further use.

While the bottom 26 is shown as flat, it may be corrugated to present to the material a larger cooling area for the same space. Also this construction separates the material into several parts, each part having an inverted triangular cross-sectional area. Hence, all material is in close contact with the cooling surface.

It is also contemplated that a complementary cooling action may be realized by causing a countercurrent of air to flow over the top surface of the material. This air might be injected through chute 22 and flow out through chute 20.

In addition, without changing the structure, hot water or steam may be employed to heat bottom 26, in which case the device may be employed as a drier.

Obviously those skilled in the art may make various changes in the details and arrangement of parts without departing from the spirit and scope of the invention as defined by the claims hereto appended, and I wish therefore not to be restricted to the precise construction herein disclosed.

Having thus described and shown an embodiment of my invention, what I desire to secure by Letters Patent of the United States:

1. In a vibratory conditioner and conveyer, the combination, with a deck having an imperforate bottom lying in a generally horizontal plane, of a base, electro-magnetic vibratory motor means constructed and arranged to operate at a frequency not less than 3000 cycles per minute and including an inclined vibrator bar connected below and to said deck and to said base and supporting said deck from said base, said motor means operating to vibrate said deck with movement having both a vertical and a horizontal component of movement whereby granular materials thereon will be conveyed while the particles thereof form a fluid bed, and means for conditioning the temperature of said imperforate bottom to condition said bed.

2. In a vibratory conditioner and conveyer, the combination with a deck having an imperforate bottom lying in a generally horizontal plane, of a base, electro-magnetic vibratory motor means constructed and arranged to operate at a frequency not less than 3000 cycles per minute and including an inclined vibrator bar connected below and to said deck and to said base, said motor means operating to vibrate said deck with movement having both a vertical and a horizontal component of movement whereby granular materials thereon will be conveyed while the particles thereof form a fluid bed, and means for conditioning the temperature of said imperforate bottom to condition said bed.

3. In a combination cooler and conveyer, the combination with a base, of a substantially horizontal deck providing a flat bottomed material supporting and conveying trough, means for vibrating and supporting said deck comprising a vibratory non-rotary continuous circuit electric motor constructed and arranged to vibrate said deck at a frequency not less than 3000 cycles per minute and positioned below said deck and above said base and having relatively movable parts attached respectively to said deck and base, said means being so constructed and arranged that upon operation of said motor said deck will be given a vibratory motion having both a horizontal and a vertical component of movement to convey material thereon while forming it into a fluid-like bed, and means for cooling the deck to cool the material forming said fluid-like bed as aforesaid.

4. In a combination cooler and conveyer, the combination with a base, of a substantially horizontal deck providing a flat bottomed material supporting and conveying trough, means for vibrating said deck comprising a vibratory non-rotary continuous circuit electric motor constructed and arranged to vibrate said deck at a frequency not less than 3000 cycles per minute and positioned below said deck and above said base and having relatively movable parts attached respectively to said deck and base, said means being so constructed and arranged that upon operation of said motor said deck will be given a vibratory motion having both a horizontal and a vertical component of movement to convey material thereon while forming it into a fluid-like bed, and means for cooling the deck to cool the material forming said fluid-like bed as aforesaid.

JAMES A. FLINT.
